(57) **CLAIM**

The ornamental appearance of an air delivery device, as shown and described.

DESCRIPTION

FIG. 1 is a perspective view of an air delivery device according to an embodiment of our design; and, FIG. 2 is a top view thereof.

The broken lines showing environment or structure of the air delivery device are for illustrative purposes only and form no part of the claimed design.

The dotted lines represent the border between claimed and non-claimed subject matter and form no part of the claimed design.

The stippling in FIGS. 1 and 2 is used to indicate shading.
